UNITED STATES PATENT OFFICE.

FRANK E. HATCH, OF RUTHERFORD, NEW JERSEY.

BOX-COVERING MACHINE.

Application filed July 16, 1920. Serial No. 396,823.

To all whom it may concern:

Be it known that I, FRANK E. HATCH, a citizen of the United States, and a resident of Rutherford, in the county of Bergen and 5 State of New Jersey, have invented certain new and useful Improvements in Box-Covering Machines, of which the following is a specification.

This invention relates to box covering machinery and particularly to machinery for covering the sides of paper boxes with gummed paper strip of suitable width from rolls of the same.

The main object of the invention is to 15 provide improved means for wrapping or placing the gummed paper strip on the box body and securing it on all parts to form a neat and workmanlike appearance. An other object is to provide for turning over 20 and securing one of the side edges of the paper strip to the bottom edges of the box, and still another object is to provide means for turning over and securing the other side edge of the strip to the inside of the top 25 edges of the box.

A further object is to provide a progressive wrapping of the paper strip on the box body, and a progressive turning over and securing of the edges thereof, and also to 30 provide means for accomplishing these operations simultaneously.

Still another object is to provide convenient and separate means to bring the wrapping means and the edge turning means into 35 and out of operation.

Other features include means for forming neat folds at the corners of the bottom of the box, and special means for securing the strip at the insides of the corners at the top 40 edges of the box.

The means I prefer to employ for accomplishing the above objects, together with other features not hereinbefore mentioned but which will appear as the description 45 progresses, are illustrated in the drawings accompanying and forming part of this specification.

Figure 1 of the drawings is a side elevation of a portion of a box covering machine embodying my invention.

Fig. 2 is a plan of the same.

Fig. 3 is an enlarged sectional side elevation of a portion of the mechanism of Fig. 1, taken from the opposite side.

Fig. 4 is an enlarged detail front eleva-

tion partly in section of part of the mechanism of Fig. 1.

Fig. 5 is a diagrammatic detail side elevation showing the operation employed in folding the corners of the strip at the bottom of a box.

Fig. 6 is a detail front elevation partly in section of the members 40', 41 and 42, and a portion of a box.

Fig. 7 is a side elevation of a modified 65 form of the invention, and

Fig. 8 is a front elevation of the same.

Like characters of reference refer to like parts in all the figures of the drawings.

In connection with the form of my invention which is illustrated in Figs. 1 to 6 inclusive, it is necessary to employ means for mounting a roll of paper strip, means for gumming the paper strip on one side, and means for guiding the paper strip to a predetermined position, all of which means are well known in the art. As the operation of all of these instrumentalities precedes the operation of my improvements, for the sake of clearness the former have not been shown 80 in the drawings.

My improved box covering mechanism is shown attached to a machine bed B, a portion only of which is shown, said portion being that at the delivery end. The roll of 85 paper strip, the means for mounting the same, the gumming means, and the guiding means being situated at the forward part of the machine are therefore not shown, except a portion of a frame which embodies 90 the posts 3 and rods 4 which I employ to support mechanism hereinafter to be described.

On the end portion of said bed B I mount 95 means for holding box bodies, and for this purpose any suitable means may be employed. I find it very advantageous to mount the box holding means on an extension of the frame B at the side thereof and designated by the numeral 2. Preferably 100 the box holding means are adapted to be rotated, so that the box body can also be rotated, and to accomplish this result I provide a shaft, such as 5, which is rotatable in the bearing 6 by suitable means (not shown), 105 and on said shaft I mount a box form such as 7, suitably held on the shaft 5, as by means of the bracket 8 which is secured by screws to the form 7 and has a hub 9 with a hole of proper size to accommodate the shaft 5 to 110

which it is secured. The form 7 may be made of any desired size to suit the particular size of box being covered, and changes from one size to another can be readily made 5 by removing the screws in the bracket 8 and changing to the form desired, or an adjustable form such as is well known in the art can be used. The box bodies of the proper size slip onto the form 7, and can then be 10 given a single revolution and then remain at rest. The mechanism to control the amount of the rotation is not shown, as several types of mechanism for this purpose are well known in this art and any suitable type 15 can be employed.

The paper strip is designated by the letter S and is shown as passing from the left hand portion of the machine toward the right with the gummed side underneath. The box bodies fit on the form 7 with a certain degree of looseness, and I have therefore provided means to maintain them in position on the form, and preferably employ a rotatable disk such as 10 to 20 bear on said box body and keep it in place on the form 7. The disk has a stem 11 which is adapted to turn in the hole 12 in the end portion of the lever 13, said lever being mounted in a bracket 14 adjustable on the 25 machine bed B. A flexible member 15, attached to the lever 13, and passing over a pulley 16, connects at its other end with a weight 17, so as to normally cause the lever 13 and disk 10 to be pulled toward the box, 30 thus keeping enough pressure on the box body to hold it in place on the box form.

If now the end of the paper strip is attached on one of the sides of the box and the box form and box are rotated slowly for 40 one turn, the paper strip will be drawn to the right and onto the sides of the box, covering the same. It is necessary, however, to provide a means of pressing the paper quite strongly against the box sides, and I preferably provide a cylindrical roll, such as 18, that will act in a progressive manner immediately after the strip is attached to the box body. It is necessary that the roll 18 shall follow up the sides as the box is rotated, so 45 that a good firm contact will be made by the gummed paper strip at all points on the box sides. This means that the roll must move up and down to keep pressing on the box sides, and to always maintain sufficient 50 pressure to make a good contact of the gummed surface.

The means I prefer to employ for this purpose embody a pair of levers, such as 60 19, which may be of any suitable form and are pivoted as at 20, on suitable supports such as the brackets 21 on the rod 4. The goose neck levers shown are very advantageous and it is preferable that they be connected by some suitable means such as 65 the bar 22. I prefer to mount the roll 18 on

a shaft such as 23, passing through the free ends of the levers 19, said roll being rotatable on the shaft.

It will be seen that the roll 18 will press the paper strip onto the box body by gravity or 70 by the combined weight of the roll, shaft 23, bar 22 and part of the weight of the levers 19, so that good contact will always be made between the paper and the sides of the box. One complete turn of the box 75 form effects the wrapping of the box with paper strip, which overlaps at the point where it was first placed in contact by hand. In actual working conditions, a cutting-off device is necessary, but I plan to use one of 80 several well known forms, and such a device is omitted in the drawings for the sake of clearness.

The paper strip overlaps the top and bottom edges of the box, and means are provided to turn over the edges of the strip and press them into contact with the adjacent edges of the box. Loosely mounted on the shaft 23 are two links or arms 24, at the free ends of which is placed a shaft 25 secured in suitable holes in said links. A roll 26 rotates freely on the shaft 25 and an adjustable flange 27 is mounted on the roll 26 nearest to the top edges of the box. Mounted on the roll 18 next to the bottom 95 edges of the box is an adjustable flange 28, which on the rotation of the box form 7 creases and folds down the edge of the paper strip and causes it to adhere to the bottom edges of the box. At the end of the roll 26 adjacent to the bottom edges of the box and mounted to turn on the shaft 25 is a disk 30. Said disk is next to the collar 29, secured fast to the shaft 25, and is provided with a lobe or projecting portion 31. A friction disk 32 of suitable material is interposed between the disk 30 and the end of the roll 26. 33 is a collar fast on the shaft 25, and 34 is a spring, placed in a recess in the roll 26 and bearing on the friction disk 32 which is also provided with driving pins 32' connecting to the roll 26. There is a pin 35 on the lobe 31 of the disk 30, and a latch 36, mounted on a lug on the link 24 nearest to said disk 30, and the latch 36 normally holds the pin of the disk 30 so as to prevent the latter from turning. The links 24 swing freely and allow the roll 26 to turn by contact with the box as the box progresses in its rotation, and the friction disk 32 pressing against the disk 30 is continually tending to turn the latter but is of course normally prevented by means of the latch 36 engaging the pin 35. On the link 24 next to the latch 36 is an arm 37 having a roll 38 and a tail 39. At the time when a corner of the box is about to pass the roll 26, the roll 38 moves downward, causing the movement of the arm 37 and tail 39. The tail 39 strikes the pin 40 on

110
115
120
125
130

the latch 36 and the latter is accordingly moved upward and releases the pin 35 on the disk 30 so that the latter can turn under the influence of the friction disk 32. The 5 disk 30 accordingly turns once and is stopped by the engagement of the latch 36 and pin 35, and is held until the next corner of the box comes along, whereupon the operation is repeated, and so on throughout 10 the rotation of the box body.

The position and shape of the lobe or projection 31 are such that the edge of the paper strip is creased and folded down at the part immediately before the corner, as 15 illustrated in Fig. 5. The flange 28 on the roll 18, rolls down the edge at the bottom of the box and presses it into contact therewith uniformly except at the part immediately before a corner. At such points a section 20 has already been pressed down so that the flange 28 turns down the following portion of the strip edge in such a position as to lap over the part first pressed down and forms a beveled fold at that point. 25 Sufficient moist gum is on the paper so that some spreads and causes adhesion at the lap.

The flange 27 on the roll 26 turns over the edge of the paper strip next to the top 30 edges of the box so that it is at right angles to the adjoining side of the box. Hung on the shaft 23 is an arm 40' having a pendulous weight 41, and a bent wire finger 42, which presses against the box edge, and acts to 35 turn under the edge of the paper strip from its last-mentioned position at right angles to the box side, to one approximately at 45 degrees thereto or to any other angle suitable for this operation.

40 Mounted on the shaft 23 is an arm 43, placed near the end of the roll 18, and at the free end of said arm is pivoted a lever 44 which carries a cylindrical roll 45, and a triangular corner presser 46, both mounted on a pin 47. A coil spring 48 causes the lever 44 to press the roll 45 and corner presser 46 against the inside edges at the top of the box and also to press the turned down edge of the paper strip into contact 45 with the same. The roll 45 is for rolling the edge of the paper strip against the inside of the top edges of the box at all points except the corners, after the strip has been acted on by the finger 42. The 50 corner presser acts on the inside of each corner as it comes in contact with it by reason of the rotation of the box. A corner comes against one of the points of the presser, presses against it and turns the presser so that the succeeding corner comes in contact with the next point of the presser.

When the boxes are placed on the form 7 before the wrapping and edge turning are done, it is necessary to provide means to 55 withdraw certain parts sufficiently far away

from the box form as will allow the box to be put in position on said form. Any suitable means may be used to effect this, but preferably I employ a lever such as 49 pivotally mounted on a bracket 50 on one of the 70 rods 4, which lever has a pin 51 which will come against one of the levers 19 when the lever 49 is swung upward. A rod 52 connects the lever 49 to a lever 53 on which is a treadle 54, so that pressure of the foot on 75 the treadle will cause the upward movement of the levers 19, rolls 18 and 26, disks 30 and 32, and links 24. Pressing downward on the projecting pin 47 releases the roll 45 and corner presser 46 from the box 80 edge when a box is in position and allows one to be placed if none is on the form.

The operation of my improved box covering mechanism illustrated in Figs. 1 to 6 inclusive, is as follows;

The paper strip from the roll of the same has been brought through the gumming and guiding devices hereinbefore-mentioned and its end hangs free at a convenient distance from the form 7. The operator first withdraws the disk 10, presses the treadle 54, which causes the lever 49 to raise the levers 19, rolls 18 and 26, and withdraws the roll 45 and presser 46 by means of the pin 47. The operator then places an uncovered box 90 body *b* on the form 7, and then brings the disk 10 against the box body and it is held in place by means of the lever 13, member 15, pulley 16, and weight 17. The end of the paper strip is now brought over the uppermost corner of the box and placed with the gummed side in contact with the box, underneath the roll 26. The mechanism for turning the shaft 5 is now caused to operate 100 and the shaft is given one turn and the box 105 form and box turn clockwise. The paper strip *S* is drawn to the right and is wrapped around the box sides and pressed down, first by the roll 26 and afterwards by the roll 18, producing a smooth and unwrinkled contact with the box body. The edges of the paper strip project over the edges of the box at both the top and bottom edges thereof. As the edge of the paper strip adjacent to the bottom of the box comes to the 115 flange 28, it is turned over at right angles and pressed against the bottom edges of the box. As the corners of the box come within range of the roll 26, the disk 30, and the flange 27, the said disk 30 is caused 120 to rotate as hereinbefore described and attaches a short section of the strip edge next following the corner, to the bottom edge of the box at that part. As the corner continues on to the flange 28, the latter continues to turn down the strip edge and causes it to lap over at the corner forming a beveled or mitered fold as previously described. The flange 27 is now turning down the other 125 edge of the strip at right angles to the box 130

sides, the finger 42 is following the above operation by turning the folded down strip edge still farther, under the edges of the box at the top, thereof, and the roll 45 presses it into its final position in firm contact with the inside edges of the top of the box. The corner presser 46 acts as hereinbefore described, the strip is cut off by the proper mechanism, and the box and form 7 come to rest. The box is removed after moving back the lever 13 and disk 10, and after the levers 19, rolls 18 and 26, have been raised by means of the treadle 54, and after the roll 45 and corner presser 46 have been released by pressing on the pin 47, and is then replaced by an uncovered box body and the operations proceed as before.

In the modification illustrated in Figs. 7 and 8, the extension 2 of the frame B carries a bearing 6 in which is journaled the shaft 5. The box form 7 is mounted on the shaft 5 so as to turn with said shaft, and several sizes of forms may be provided to fit the boxes it is desired to cover. Levers 19, 25 similar to those described in the preferred form of my invention and suitably mounted, carry the cylindrical roll 18 which presses the paper strip S into contact with the box, and a fixed flange 60 on said roll starts the 30 turning over of the right hand edge of the paper strip so that it is at substantially right angles to the box sides.

A grooved roll 61 is mounted on the lever 62 by means of the screw 63, and the lever 62 is secured fast on the shaft 64 by means of the clamp screw 65. The shaft 64 is journaled in the hub 66 of the adjustable lever 67 journaled on a bracket 68 secured to the frame extension 2. The lever 67 has a roll 69 which works against a cam 70 secured to the shaft 5, said roll being caused to press against said cam by means of the coil spring 71 attached at one end to the lower end of the lever and at the other end to a pin on the frame extension 2. An arm 72 is secured by a set screw 72' to the shaft 64 and has a pin 73 in line with an arm 74 journaled on the shaft 64. The arm 74 is connected to a link 75 having a slot 76, a bridge piece 77, and a roll 78 on the bridge piece bearing on the cam 79. A coil spring 80 is connected at one end to the link 75 and at the other end to a pin in the bracket 81 which is secured to the frame extension 2. The cam 70 has 55 four lugs 82 and the cam 79 has four depressions 83, one lug and one depression being provided for an operation that occurs at each corner of the box. A coil spring 84, having hooks 84' connecting respectively to the lever 62' and the lever 67, causes the lever 62 to normally press the grooved roll 61 against the top edges of the box, and when the gummed paper strip is wrapped around the box with its edges overhanging the adjoining box edges, the roll 61 creases and

presses down the paper of said strip edge next the bottom of the box onto the bottom edges thereof and causes it to adhere thereto. As a corner of the box reaches the roll 61, the roll 78 on the link 75 moves into one of the depressions 83 of the cam 79, causing the link 75 to move the arm 74, which then moves the arm 72 by means of the pin 73 and said arm 72 rocks the shaft 64. Consequently the arm 62 swings upward, carrying the roll 61 out of engagement with the edge of the paper strip. One of the lugs 82 on the cam 70 now moves the lever 67, thus moving the shaft 64 to the right, and the arm 62 and roll 61 are then allowed to go back into contact with the edge of the paper strip, folding down the same at the corner in a beveled or mitered fold or lap. This is repeated at each corner of the box.

Mounted on the frame extension 2 on a pivot 85 is a lever 85' pressed upward by the spring 85^b, and at the free end of said lever is an adjustable bent wire member or finger 86 held in a short rocker arm 87 pivoted at 88. A coil spring 89 normally tends to press the finger 86 against the inside of the top edges of the box. The finger 86 has a bent portion 90 which turns under the edge of the paper strip and a portion 91 which presses said edge against the inside of the top edges of the box. Also pivoted on the lever 85 is a rocker arm 92 carrying a roll 45 and a triangular corner presser 46, both journaled on a pin 47. A coil spring 93 causes the rocker arm to normally rest against a stop pin 94.

In order that the machine shall be adjustable to boxes of different sizes, the lever 67 is adjustable in length by means of a slotted portion held on the lower portion by suitable bolts 67'. The bridge piece 77 is adjustable on the link 75, and two opposite lugs on the cam 70 are adjustable to or from the other two by reason of the cam being formed in two parts held together by suitable screws such as 70'. Also the depressions in the cam 79 are adjustable in pairs by reason of the cam being constructed in two parts held by screws such as 79'.

What I claim is:—

1. In a box covering machine, the combination with means for wrapping a gummed paper strip around the sides of a box, of mechanism for turning over one of the side edges of said strip and attaching it to the bottom edges of the box which mechanism includes means effective to form a flat beveled or mitered fold in said strip edge at each corner of the box bottom.

2. In a box covering machine, the combination with box holding means, means for rotating the same, and means cooperating therewith for wrapping a gummed paper strip around the sides of a box, of means for turning over one of the side edges of said

strip and attaching it to the inside of the top edges of the box, which include the flange of a rotating member for the initial turning, a guide to turn under said strip edge after the initial turning, and a pressure roll to operate after said guide.

3. In a box covering machine, the combination with box holding means, means for rotating the same, and cooperating means for 10 wrapping a gummed paper strip around the sides of a box which include a cylindrical roll, and means for mounting the same, of means for turning over one of the side edges of said strip and attaching it to the inside 15 of the top edges of the box which include a lever pivoted on the mounting of the cylindrical roll, and a rotary pressure roll supported by means of said lever and effective to 20 press the strip edge onto the inside of the top edges of the box.

4. In a box covering machine, the combination with box holding means, means for rotating the same, and means cooperating therewith for wrapping a gummed paper 25 strip around the sides of a box, of means for turning over one of the side edges of said strip and attaching it to the inside of the top edges of the box, which means include a pressure roll and a corner presser operating 30 on a common center.

5. In a box covering machine, the combination with box holding means, means for rotating the same, and means cooperating therewith for wrapping a gummed paper 35 strip around the sides of a box, of means for turning over one of the side edges of said strip and attaching it to the inside of the top edges of the box which include a guide which turns under said strip edge, a yielding member on which said guide is mounted, a pressure roll to operate after said guide, and a spring-controlled arm on which said roll is mounted.

6. In a box covering machine, the combination with box holding means, means for rotating the same, and cooperating means for wrapping a gummed paper strip around the sides of a box, of means for turning over one of the side edges of said strip and attaching it to the inside of the top edges of the box which include a triangular corner presser to finish the inside of the corners and means for yieldingly mounting the corner presser.

7. In a box covering machine, the combination with mechanism for wrapping a gummed paper strip around the sides of a box, and mechanism for turning over one of the side edges of said strip and attaching it to the bottom edges of the box, of means for making a beveled fold in said strip edge at each corner of the box bottom, which means include a rotary member that is brought into and out of action intermittently.

8. In a box covering machine, the combi-

nation with mechanism for wrapping a gummed paper strip around the sides of a box, and mechanism for turning over one of the side edges of said strip and attaching it to the bottom edges of the box, of means for 70 making a beveled fold in said strip edge at each corner of the box bottom, which means include a rotary disk having a projecting lobe, a latch pin on said disk, a latch to hold said disk by said pin, and means actuated by 75 the box corners to trip said latch.

9. In a box covering machine, the combination with box holding means, means for rotating the same, and means cooperating therewith for wrapping a gummed paper 80 strip around the sides of a box, of means for turning over the two side edges of said strip and attaching them respectively to the top and bottom edges of the box which means are controlled in their operating movements by 85 contact on the sides of the box.

10. In a box covering machine, the combination with box holding means, means for rotating the same, and means cooperating therewith for wrapping a gummed paper 90 strip around the sides of a box, of means for turning over one edge of said strip and attaching it to the top edges of the box which means are controlled in their operating movements by 95 contact on the box.

11. In a box covering machine, the combination with box holding means, means for rotating the same, and means cooperating therewith for wrapping a gummed paper 100 strip around the sides of a box, of means for turning over one of the side edges of said strip and attaching it to the bottom edges of the box and to form beveled folds at the box corners, which means include a member to turn down a portion of said strip adjacent to each corner and a member to operate after said first-mentioned one to turn down the remainder of the strip edge including the beveled folds at the corners of the box.

12. In a box covering machine, the combination with box holding means, means for rotating the same, and means cooperating therewith for wrapping a gummed paper strip around the sides of a box, which means embody a revolving cylindrical roll, of means for turning over one of the side edges of said strip and attaching it to the bottom edges of the box and means for forming beveled folds at the box corners, which means include a member to turn down a portion of said strip adjacent to each corner and a member revolving with the roll to operate after said first-mentioned member to turn down the remainder of the strip edge including the beveled folds at the corners of the box.

13. In a box covering machine, the combination with box holding means, means for rotating the same, and means cooperating therewith for wrapping a gummed paper strip around the sides of a box, which means 130

embody a revolving cylindrical roll, of means for turning over one of the side edges of said strip and attaching it to the bottom edges of the box and for forming beveled folds at the 5 box corners, which means include a rotating disk having a projecting lobe for turning down a portion of said strip edge adjacent to each corner and an adjustable flange on said roll to operate after said disk to turn 10 down the remainder of the strip edge including the beveled folds at the corners of the box.

14. In a box covering machine, the combination with box holding means, means for 15 rotating the same, means cooperating therewith for wrapping a gummed paper strip around the sides of a box which include two cylindrical rolls one operating after the other and one of which swings on the axis 20 of the other, of mechanism for turning down one of the side edges of the paper strip and attaching it to the bottom edges of the box and for forming a beveled fold at each corner of the box bottom, which include a 25 flange on the last of said rolls, a lobed disk on the axis of the first of said rolls, and means whereby the lobed disk turns down a portion of the strip edge before each corner.

15. In a box covering machine, the combination with box holding means, means for 30 rotating the same, and means cooperating therewith for wrapping a gummed paper strip around the sides of a box, of means for turning over one of the side edges of said strip and attaching it to the inside of the 35 top edges of the box which include a cylindrical roll rotatable on an axis parallel with the box axis to press down the strip edge onto said inside of the top edges of the box 40 which means are mounted on an up and down moving member and spring-pressed to cause them to follow the movements of the rotating box.

16. In a box covering machine, the combination with box holding means, means for 45 rotating the same, and means cooperating therewith for wrapping a gummed paper strip around the sides of a box, of means for turning over one of the side edges of said strip and attaching it to the inside of the 50 top edges of the box which include a guide which turns under the strip edge, a pendulous arm on which the guide is mounted, and a pressing device to operate after said 55 guide.

17. In a box covering machine, the combination with box holding means, means for 60 rotating the same, and means cooperating therewith for wrapping a gummed paper strip around the sides of a box which include a pressing roll and a lever on which the roll is mounted, of means for turning over one of the side edges of said strip and attaching it to the inside of the top edges of the box 65 which means include an edge pressing roll

and a triangular corner presser mounted on a common pin, a lever on which the pin is mounted, a spring to press the lever towards the inside edge, and a second lever supported by the wrapping roll lever and supporting 70 the spring-pressed lever.

18. In a box covering machine, the combination with mechanism for wrapping a gummed paper strip around the sides of a box, and mechanism for turning over one 75 of the side edges of said strip and attaching it to the bottom edges of the box, of means for making a beveled fold in said strip edge at each corner of the box bottom, which means include a rotary disk having a projecting lobe, a latch pin on said disk, a friction driving member for the rotary disk, a latch to hold the disk by said pin, a trip lever for said latch, and a roll on said lever operated by the box corners and adapted to 80 85 effect the tripping of said latch.

19. In a box covering machine, the combination with box holding means, and means for rotating the same, of means cooperative 90 therewith for wrapping a gummed paper strip around the sides of a box and turning down the side edges of the strip which embody two cylindrical rolls operating on different axes and which bear on the box by gravity and a flange on each of said rolls 95 rotatable therewith and shiftable endwise thereon.

20. In a box covering machine, the combination with box holding means, means for 100 rotating the same, and means for wrapping a gummed paper strip around the sides of a box, of means for turning over one of the side edges of said strip and attaching it to the inside of the top edges of the box which include a presser roll, a corner presser, a movable arm to support the presser and roll, a spring to support said arm, and means to retract said roll, presser and arm. 105

21. In a box covering machine, the combination with a box holding form, means for 110 rotating the same, and means for wrapping a gummed paper strip around the sides of a box held on the box holding form, of means for turning over one edge of said strip and attaching it to the inside of the 115 top edges of the box which include a pivoted member having a plurality of flat surfaces each of which is adapted to slide along and press against said inside edges and means for yieldingly mounting the pivoted member. 120

22. In a box covering machine, the combination with box holding means, means for 125 rotating the same, means cooperating therewith for wrapping a gummed paper strip around the sides of a box, and means for turning over one edge of said strip and attaching it to the bottom edges of the box, of means for forming beveled folds at the bottom corners of the box which include a 130

feeler roll which is effective to start the operation of said bevel-fold-forming means.

23. In a box covering machine, the combination with box holding means, means for rotating the same, means cooperating therewith for wrapping a gummed paper strip around the sides of a box, and means for turning over one edge of said strip and attaching it to the bottom edges of the box,

of means for forming beveled folds at the bottom corners of the box which include a feeler roll and a feeler roll lever having a portion adapted to start the bevel-fold-forming means into operation.

Signed at New York, in the county of New York, and State of New York, this 6th day of July, A. D. 1920.

FRANK E. HATCH.
